Primary Examiner—Pamela Burgess**(74) Attorney, Agent, or Firm**—Marshall, Gerstein & Borun LLP**(57) CLAIM**

The ornamental design for a “drapery hardware bracket”, as shown and described.

DESCRIPTION

FIG. 1 is a front perspective view of a drapery hardware bracket showing our new design;

FIG. 2 is an end elevational view thereof, the opposite end being a mirror image;

FIG. 3 is a top plan view thereof;

FIG. 4 is a bottom plan view thereof;

FIG. 5 is a right side elevational view thereof; and,

FIG. 6 is a left side elevational view thereof.

The broken lines shown are for illustrative purposes only and form no part of the claimed design.
